[57] **ABSTRACT**

Irreversible epicyclic gearing connects the seat back to the seat and includes a manually rotatable shaft having an eccentric portion on which is mounted a drive gear engaged in an internal gear carried by the seat or seat back member and having limited lost motion connection with the other member.

BY *W. Buttemore,
Hubert & Selkirk*

illustrated at 12 in FIGS. 1-3, and the drive gear 58 and shaft 60 may also be identical.

In this construction the upper end of the stampings 52 and 54 are interconnected by rivets 62 which form pin-like elements performing the functions of the elements 32 in the previously described embodiment of the invention. These elements not only serve the function of establishing a driving relation with the drive gear 58, but also of course serve as the means both interconnecting and spacing the upper ends of the stampings 52 and 54.

Rotation of the shaft 60 results in oscillation of the drive gear 58 and produces angular movement between the members 50 and 56.

In this construction a different guiding support is provided intermediate the members 50 and 56. The member 50 journals the shaft 60 at the two coaxial cylindrical journal portions 64 and 66. However, the seat back bracket member 56 is in this case guidingly connected to and supported by the member 50 by reason of a cylindrical flange 68 which engages around a substantial portion of the toothed periphery of the laterally displaced abutment wall 70. In addition, the stamping 54 is provided with an arcuate depressed portion 72 forming a generally cylindrical guide wall 74 which engages a portion of the crests of the teeth on the abutting wall 70 substantially opposite the flange 68.

It will of course be understood that the drive gear 58 is journaled on the eccentric portion 76 of the shaft 60 but since this gear is in mesh with the internal gear 78 provided in the seat back member 56, it cannot provide the necessary guidance for swinging movement of the seat back.

It will be observed that in this embodiment of the invention the overall thickness of the mechanism provided at the pivot connection, exclusive of the shaft 64, is again substantially equal to the combined thickness of the material of the drive gear 58, the member 56, and the combined thickness of the two stampings 52 and 54.

It will further be observed that in both cases the drive gear has opposite flat side surfaces which respectively engage a confronting surface of one of the bracket members 10 or 50 and the confronting surface of the abutment wall 18 or 70.

What I claim is:

1. Adjustable support structure for a seat back of a reclining seat comprising
a stationary support member,
an arm member pivoted to said stationary support member,
pivot means comprising a rotatable shaft connecting said
members, said shaft having a circular cross-section first
portion defining the pivot axis between said members,
and a circular cross-section second portion eccentric to
said first portion,
irreversible drive gearing connecting said members comprising
an externally toothed annular drive gear rotatable on the ec-
centric portion of said shaft and having a series of circular
openings disposed in a circular array around and concen-
tric with said eccentric portion,
one of said members having an internally toothed recess
constituting an internal gear and receiving said drive gear
in mesh therewith, the number of teeth in said internal
gear exceeding the number of teeth in said drive gear by a
small number representing a small fraction of the total
number of teeth in said recess,
said other member having a circular array of pin-like ele-
ments extending into said circular openings, the diameter

of said array being equal to the diameter of the circular array of openings in said drive gear, the diameter of said circular openings exceeding the diameter of said elements by double the eccentricity of the eccentric portion of said shaft,

5 said one member being formed of flat metal plate-like material,
and an annular abutment on said one member closing one
10 end of the internal gear and serving to engage one side of
said drive gear to limit axial movement thereof in one
direction,
said other member having an annular portion positioned to
15 engage the other side of said drive gear to limit axial
movement thereof in the other direction,
and manually operated means for rotating shaft shaft.

2. Structure as defined in claim 1 in which said internal gear
and said annular abutment are both formed from unitary rigid
20 plate-like material, and said abutment is a gear shape laterally
stamped partially from but not severed from the sheet materi-
al.

3. Structure as defined in claim 1 in which said other
25 member is formed of plate-like material and said pin-like ele-
ments are stamped extrusions extending laterally from one
side of said other member.

4. Structure as defined in claim 2 in which said other
30 member is formed of plate-like material and said pin-like ele-
ments are stamped extrusions extending laterally from one
side of said other member.

5. Structure as defined in claim 4, said drive gear being
35 formed of plate-like metal of about the same thickness as said
members and having opposed flat surfaces in sliding contact
with the confronting surface of the annular abutment on said
one member and the side of said other member, whereby the
operating structure at the pivot connections between said
35 members exclusive of said shaft has an overall thickness about
equal to the combined thickness of said members and drive
gear.

6. Structure as defined in claim 2, said other member com-
40 prising substantially paired concave shaped portions, one of
said portions having a substantially cylindrically shaped flange
guidingly engaging the crests of the teeth of said gear-shaped
stamping.

7. Structure as defined in claim 6, said one concave shaped
45 portion having an inwardly formed arcuate portion having an
arcuate generally cylindrical area guidingly engaging the
crests of the teeth of said gear-shaped stamping in a zone
generally opposite the zone thereof engaged by said flange.

8. Structure as defined in claim 1, the annular abutment on
50 said one member having a generally cylindrical outer
peripheral portion, said other member comprising substan-
tially paired concave shaped portions, one of said portions
having a substantially cylindrically shaped flange guidingly eng-
aging the outer peripheral portions of said abutment.

9. Structure as defined in claim 8 in which said concave
55 shaped portions are formed of sheet material having stiffening
flanges around their edge portions.

10. Structure as defined in claim 9 in which said pin-like ele-
ments extend between and rigidly interconnect said concave
shaped portions.

11. Structure as defined in claim 8, said one concave-
shaped portion having an inwardly formed arcuate portion
having an arcuate generally cylindrical area guidingly engag-
ing the outer peripheral portions of said abutment in a zone
generally opposite the zone thereof engaged by said flange.
